DAVID B. SHIRK, OF BRUNNERSVILLE, PENNSYLVANIA.

Letters Patent No. 83,556, dated October 27, 1868.

IMPROVED RAILWAY CATTLE-GUARD.

The Schedule referred to in these Letters Patent and making part of the same.

To all whom it may concern:

Be it known that I, DAVID B. SHIRK, of Brunnerville, in the county of Lancaster, and State of Pennsylvania, have invented a new and improved Mode for Operating Cattle-Guards or Railroad-Gates at crossings; and I do hereby declare that the following is a full and correct description of the construction and operation of the same, reference being had to the accompanying drawings, making a part of this specification, in which—

Figure 1 is a perspective view of my improvement, in place.

Figure 2 shows the double crank-shaft, pickets, and appended weight.

Figure 3, a perspective view of the same, to show the inclination of the cranks in opposite directions on the top of the shaft.

Figure 4 shows the hinged side-lever, with its open jaw, for the reception of the crank.

The nature of my invention consists in providing a double crank-shaft, the cranks so inclined from the centre as to be readily depressed, by means of hinged levers, on the inside of the rails, placed in a reversed position, in such a manner as to be acted upon by the flange of the wheels; the crank-shaft being also weighted, and provided with pickets, to form the gate or barrier.

To enable others skilled in the art to make and use my invention, I will describe the same by reference to the drawings, which clearly illustrate the double crank-shaft, with the crank *e* inclined, say, thirty degrees to the left, and crank *e'* inclined thirty degrees to the right, from a central line on the top of the shaft. This shaft has its bearings in side pieces *B*, between the cross-ties *2 3*, and is provided with pickets *P* on top, to form the gate, and a weighty cylinder, *w*, below to keep the pickets in a vertical position. On the inside of each rail, *R*, there is a lever, *L*, hinged at the remote end from the crank at *H* to a block, or otherwise, on the cross-tie. This necessarily reverses their position, and each is actuated by the flange of the

wheels, and will tilt the gate in the direction of the moving car. To effect this tilting-operation, the loose end of the lever *L* is provided with open jaws, *J*, in which the crank plays freely, and, being inclined in the direction it is to tilt, will readily do so by the depression of the levers by the flanges of the wheels aforesaid, and thereby prostrate the gate, and keep it in that position until the last truck has passed over it, when the pending weight, *w*, will restore the gate to a vertical position, without the intervention of springs and complicated side levers, making it a very simple and efficient arrangement for the purpose.

I am aware that Moses Hall, jr., claims a cattle-guard, with its cross-shaft below the rails, and operated by springs placed on the inside of the rails, similar in position to my levers, which are depressed by the car-wheels, and tilt a gate. But I disclaim the use of springs, whether coiled and operated by a tilting-bar or otherwise.

I am aware, also, that A. C. Goodman and H. Fessler, in their patent of December 3, 1867, use a weight, appended to the outer ends of a gate, said weights being connected by lever-arms, actuated in the centre of the track. Such an arrangement I also disclaim.

Fully aware of other analogous devices, I am not aware of any arrangement in which cranks and a hinged lever are employed, operating substantially in the manner specified.

What I claim as my invention, and desire to secure by Letters Patent, is—

The arrangement of the crank *e e'*, when not in the same plane, on the top of a shaft, which shaft is provided with pickets *P*, and a central weight, *w*, appended below, and when operated by a hinged lever, *L*, with its open jaws *J*, the lever being pivoted at one end, all combined and operating substantially in the manner and for the purpose specified.

DAVID B. SHIRK.
